UNITED STATES PATENT OFFICE.

HARRY T. TULARE, OF ROCHESTER, MINNESOTA.

PHONOGRAPH.

Application filed June 25, 1923. Serial No. 647,613.

To all whom it may concern:

Be it known that I, HARRY T. TULARE, a citizen of the United States, residing at Rochester, in the county of Olmsted and 5 State of Minnesota, have invented certain new and useful Improvements in Phonographs, of which the following is a specification.

This invention relates to certain new and 10 useful improvements in phonographs, and has particular reference to a setting mechanism for the tone arms of phonographs.

It is well known that considerable difficulty is experienced with commercial phonographs in accurately setting the tone arms so that the needle of the sound box engages the sound groove of the record at the starting point of the groove. It is accordingly, 15 an object of the present invention to provide 20 means for setting the tone arms in proper position and for lowering the same to engage the needle of the sound box with the sound groove at the starting point thereof.

Another object of the invention is to provide 25 means for moving the tone arm from operative to inoperative position, or vice-versa, and means cooperating with the tone arm moving means for accurately limiting swinging movement of the same to a point, 30 whereby when the tone arm is lowered, the sound box needle will accurately engage the starting point in the sound groove of the record.

Still another object of the invention is 35 the provision of limiting means whereby the swinging movement of the tone arm will be limited to a proper point in accordance with the size of the record to be played.

With the above general objects in view, 40 and others that will become apparent as the nature of the invention is better understood, the same consists in the novel form combination, and arrangement of parts herein-after more fully described, shown in the accompanying drawings, and claimed.

In the drawings forming part of this application, like numerals of reference indicate similar parts in the several views, and wherein:

50 Figure 1 is a top plan view of a phonograph equipped with a tone arm setting mechanism constructed in accordance with the present invention.

55 Figure 2 is a view in front elevation, and partly broken away, of the device shown in Figure 1.

Figure 3 is a fragmentary sectional view shown on a larger scale, and taken substantially on the line 3—3 of Figure 2.

Figure 4 is an enlarged fragmentary 60 view showing the tone arm movement limiting device in elevation.

Figure 5 is a vertical sectional view taken on line 5—5 of Figure 4.

Figure 6 is a longitudinal sectional view 65 of the stop arm.

Referring more in detail to the drawings, the invention is shown applied to a commercial type of disk phonograph, embodying the usual casing or cabinet 5, within which 70 is located the usual horn or amplifying member 6, and above the top of which is located the usual turn table 7, adapted for reception of a disk record 8. Disposed above the turn table is the inwardly projecting tone 75 arm 9, having a sound box 10, which is adapted to receive a needle in the usual manner to engage the sound groove of the record 8 for reproducing the sound recorded thereon. In this type of machine, the tone arm 80 and horn 6 are in fixed relation to each other and pivoted to swing as the tone arm moves towards the center of the record during the playing of the record, the horn and tone arm being also vertically movable to engage 85 and disengage the needle or stylus from the record.

In accordance with the present invention, a vertical rock shaft 11 is suitably journaled 90 at the forward end of the casing in front of the horn 6, and has a rearwardly projecting arm 12, as shown in Figure 3, which is attached to the arm as at 13, so that when the shaft 11 is turned in either direction, corresponding swinging movement is imparted to 95 the tone arm and the horn. In order to prevent ready turning of the shaft 11, the same is provided with a cam lever 14 upon its upper end above the top wall 15 of the cabinet 5, which cam lever 14 is raised for permitting 100 downward movement of the rock shaft 11 for correspondingly lowering the tone arm and horn, as indicated by dotted lines in Figure 2, in which lowered position, the needle or stylus engages the sound groove 105 of the record 8. On the other hand, when the cam lever 14 is lowered to the position shown in Figure 2, the horn and sound box, as well as the tone arm is in raised position and out of engagement with the record.

110 The lower end of the rock shaft 11 is provided with a stop arm 16, which is suitably

fastened thereon as by means of a set screw 16' passing through the same, and engaging the shaft 11. The arm 16 is then caused to swing with the shaft 11 as the latter is rotated by movement of the tone arm inwardly in playing the record, and a stop means of novel construction is located in the path of the arm 16, so as to initially limit its movement to a point wherein tone arm 9 is disposed with the stylus directly above the starting point of the groove in the record 8. This means embodies a guide 18 preferably in the nature of a vertical bracket fastened to the bottom of the cabinet 5 and having vertical end flanges in which is guided a vertically movable plate 19 having stop lugs 20 and 21, which are arranged in the path of the arm 16, selectively, and in a manner which will presently become apparent. As will be seen from an inspection of Figure 4, the stop lug 20 has a flat side disposed in a vertical plane inwardly of the flat side of the lug 21 so that the shaft 11 will have to be rotated a greater distance to engage the arm 16 with the lug 20 than is necessary to engage the same with the lug 21. In this manner, when the lug 20 is disposed in the path of the arm 16, the movement of the tone arm 9 is limited to the proper point when a small size record is to be played, while when the lug 21 is disposed in the path of said arm 16, the tone arm 9 is allowed to swing a lesser distance for properly positioning the stylus with respect to the starting point of the groove in a larger record.

The upper end of the slide 19 is attached to the lower end of a rod 22 which extends upwardly through the top 15 of the cabinet 5 and terminates in a knob 23 by means of which, the slide 19 may be conveniently raised or lowered in order to place the desired one of the lugs 20 and 21 in operative relation to the arm 16. Means is provided for retaining the slide 19 in any of its vertically adjusted positions such as a spring pressed plunger or ball catch 24 carried by the bracket 18 and adapted for selective reception within suitable sockets 25 provided in superimposed relation on the back of the guide 18. As shown in Figure 6, the arm 16 is of peculiar construction embodying a main section with a pivoted member 26 upon the outer end thereof, which member is hinged on the pin 27 for vertical swinging movement and has a longer inner edge portion 28 whereby the outer end of the member 26 is normally maintained horizontal, as shown in the above mentioned figure, and by means of which the arm is allowed to tilt under the influence of the lugs 20 and 21, as will presently become apparent.

As shown in Figures 2, 4 and 5, the lugs 20 and 21 are in spaced super-imposed relation so that when the tone arm and horn are lowered, to engage the stylus with the record,

the arm 16 is lowered to a point wherein its outer end portion 26 may pass between said lugs as it moves with horn and tone arm during the playing of the record. When the record is played, the arm 16 will have moved to the opposite sides of the lugs 20 and 21, and as it is necessary to raise the arm 16 with the tone arm 9 in order to disengage the stylus from the record and then swing the tone arm back to starting position, it is necessary to provide means whereby the arm 16 may readily pass in the opposite direction without being prevented from having this movement by the lugs 20 or 21. For this purpose, the lower edges of the lugs are of cam formation or curved as at 29, so that the outer end 26 of the arm 16 will engage the curved surface, and be caused to tilt downwardly. When the member 26 of the arm 16 passes the lower point on the edge 29, it will immediately swing upwardly to the position shown in Figure 6, so as to be in position to engage the flat side of the lug arranged in its path upon the positioning of the tone arm upon a new record to be played.

In operation, the cam lever 14 is lowered to the position shown in Figure 2, and is then rotated to the right, so as to swing the tone arm 9 in the same direction out of the way. The record is then placed upon the turn-table, and the lever 14 is swung to the left until the member 26 of the arm 16 strikes against the flat side of the lug 20 or 21, which is arranged in its path. It is of course to be understood that if a ten-inch record is to be played, the slides 19 will be lowered so as to place the lug 20 in the path of the member 26, and if a twelve-inch record is to be played, the slides 19 will be raised to dispose the lug 21 in the path of said arm member 26. In this way, the movement of the tone arm 9 to the left is limited to a proper point wherein the stylus is disposed directly above the starting point of the groove in the record. When the movement of the lever 14 and tone arm 9 is then limited, the lever 14 is then raised so as to permit of the tone arm and horn together with the shaft 11 to lower to the position shown by dotted lines in Figure 2. When so disposed, the needle or stylus is arranged in the groove of the phonograph and the member 22 of the arm 16 disposed in a horizontal plane between the lugs 20 and 21. Upon completion of playing of the record, the arm 16 will have moved past the lugs 20 and 21 so as to lie at the opposite sides thereof. The lever 14 is then lowered so as to raise the tone arm and connected part to the full line position of Figure 2, for disengaging the stylus from the record, and then the lever 14 is turned toward the right so as to again return the tone arm to an inoperative position, where it is out of the

way for permitting free placing of a new record upon the turn-table. When the lever 14 is thus turned to the right, the member 26 engages the inclined lower edge of the lug 20 or 21 disposed in its path and is thereby caused to tilt against the action of the weighted end portion 28 so that the arm 16 may readily pass this lug. As soon as the member 26 passes the lug, it again swings back to normal horizontal position, so as to be properly disposed for engaging the flat side of the lug when the tone arm is again swung for playing a new record.

From the foregoing description it is believed that the construction and operation, as well as the advantages of the invention will be readily understood and appreciated by those skilled in the art.

Minor changes may be made without de-

parting from the spirit and scope of the invention as claimed.

Having thus described my invention, what I claim as new, and desire to secure by Letters-Patent, is:

In a phonograph, a vertically disposed shaft journalled for turning movement, means for raising and lowering the shaft, a tone arm mounted upon the shaft, a stop arm carried by the shaft, a member pivoted upon the stop arm and having an end portion projecting beyond the end of the stop arm, a slide member mounted for movement parallel with the shaft, means for moving the slide member, and a lug carried by the slide member and disposed toward the shaft.

In testimony whereof I affix my signature.

HARRY T. TULARE.
